UNITED STATES PATENT OFFICE.

WILLIAM F. TROAST, OF LANCASTER, PENNSYLVANIA, ASSIGNOR TO THE SLAYMAKER-BARRY COMPANY, OF SAME PLACE.

PADLOCK.

SPECIFICATION forming part of Letters Patent No. 574,961, dated January 12, 1897.

Application filed June 26, 1895. Serial No. 554,094. (No model.)

To all whom it may concern:

Be it known that I, WILLIAM F. TROAST, a citizen of the United States, residing at Lancaster, in the county of Lancaster and State of Pennsylvania, have invented certain Improvements in Locks, of which the following is a specification.

This invention relates to improvements in that class of shackle-locks in which the case containing the locking mechanism is formed with the shackle itself; and the objects of the improvements are, first, to produce a cheap strong lock in which the parts are so compacted as to render it available for use in securing bicycles and in locking other structures where a padlock is available, and, second, to increase the number of changes in the structure, whereby there may be increased security of the lock against tampering.

10 The invention consists in the construction and combination of the various parts of the locking mechanism.

20 The invention consists also in the construction and combination of various details, as hereinafter fully described, and then pointed out in the claims.

The invention is illustrated in the accompanying drawings, forming a part of this specification, and in which—

30 Figure 1 is a side view showing the free ends of the shackle locked together. Fig. 2 is a section on broken line 2 2 of Fig. 1. Fig. 3 is a side view of the swinging arm of the shackle detached, showing the hinge-spring in place; Fig. 4, a similar perspective view, but with the hinge-spring removed; Fig. 5, a similar perspective view of the hinge end of the "fast arm" of the shackle; and Fig. 6, a perspective view of the fast arm of the shackle 35 in place; Fig. 7 is a top plan view of the lock-case, the closing-plate of the bolt-case being removed. Fig. 8 is an edge view of the lock from the direction of arrow 8, Fig. 1; Fig. 9, a vertical section on broken line 9 9, Fig. 11; and Fig. 10, a similar section on broken line 10 10 of Fig. 12. Fig. 11 is a section of the lock longitudinally of the lock-case, showing the 40 swinging arm of the shackle engaged by the locking-bolt; and Fig. 12, a similar view, the

55 swinging arm of the shackle being disengaged from the bolt. Fig. 13 is an end view of the butt of the key-head; Fig. 14, a perspective view of the open end of said key-head; Fig. 14½, a front perspective view of a modified form of key-head, and Fig. 15 a side view of two sizes of the key-head. Fig. 16 is a top perspective view of the locking-bolt; Fig. 17, a similar bottom view thereof; Fig. 18, a view of one form of key; Fig. 19, a view of a second form of key; Fig. 20, a face view of a ward-plate, and Fig. 21 a similar view of a spacing-plate. Fig. 22 is a vertical section on broken line 22 22 of Fig. 11, 60 and Fig. 23 a similar section on broken line 23 23 of Fig. 12. Fig. 24 is a perspective view of the operating mechanism, the actuating key-head being in the position occupied thereby as it disengages the bolt from the swinging end of the shackle. Fig. 25 is a sectional perspective view of the lock-case, the operating mechanism being removed. Fig. 26 is a section on broken line 26 26 of Fig. 8.

65 Similar letters indicate like parts throughout the several views.

70 This lock comprises two segments, forming arms A and B of a shackle, hinged together at one end and detachably connected at the other. The extremities of said hinged ends 75 are halved and form heads a and b, and in the inner or meeting faces of said heads are registering recesses a' and b', respectively, which form the receptacle for a coiled spring c, adapted to separate the swinging ends of 80 arms A and B. In the rims of recesses a' b' are oppositely-located registering grooves a² b², the grooves a² forming a passage into a socket a³ in the body of arm A and the grooves b² a passage into a socket b³ in the body of 85 arm B. The outer grooves a² b² also permit the tool for reaming out sockets a³ and b³ to 90 be properly directed.

95 In hinging the arms A B together the spring c is seated in one of the recesses, say recess b', with one end, c', engaging socket b³, the other end, c², extending outward, as seen in Fig. 3. The head a is then placed over head b, in doing which end c² of spring c is engaged in socket a³. A hinge-pin P is inserted 100 through perforations P' in the centers of recesses a' b'. The head P² of hinge-pin P is

of such width as to lap the rims of recesses a' b' , and when the reduced end P^3 is riveted over to secure the hinge-pin P in place it is riveted over a washer P^4 , which also laps the rims of said recesses. The head P^2 and washer P^4 are so extended over said rims as to relieve the backs of recesses a' b' from undue pressure, whereby they might be forced inward and compress spring c , interfering with the action thereof.

For the purposes of this specification the end of the lock-case in which the key is inserted is called the "front" and that in which the swinging end of the detachable arm of the shackle is locked the "rear" or "back," and the device in the lock-case through which the key actuates the locking-bolt is called the "key-head." When engaged by the key, this key-head practically becomes a portion thereof, fulfilling the functions of a bit on the key.

On the outside of the swinging end of arm A is a tangential tubular lock-case D, having on the top thereof a radial tubular bolt-case E, located near the rear end of said lock-case. From beneath and somewhat forward of the center of the bolt-case the bore of the lock-case is of reduced diameter to its rear end, so as to form a segmental shoulder d in the lower part of said lock-case from the point of intersection therewith of the bolt-case on one side to the point of intersection thereof on the other side.

In the lock-case is a revolvable key-head F, comprising a segment F' of a tube, closed at the front end by an annular plate F^2 of the diameter of the interior of the lock-case and having therein two perforations f , adapted to receive the prongs K' of the key. Normally the segment F' is turned with its open side toward the mouth of bolt-case E, and at all times its rear end, which is open, bears against shoulder d .

A locking-bolt G plays vertically in bolt-case E, and has its lower or locking end bifurcated, as shown in Figs. 16 and 17, the slot g , separating the jaws, being of sufficient width to receive therein bar e , extending across the bottom of bolt-case E, whereby the bolt is prevented from turning in its case. In their normal position the jaws of bolt G project below the bottom of bolt-case E and extend into lock-case D, the rear jaw g' engaging a notch n in the reduced end N of arm B. The outer edge of the bottom of jaw g' of said bolt G is beveled, as shown at g^2 , Fig. 17, and is adapted to be engaged by the beveled end of head N' of the reduced end N of shackle-arm B, so that head N' may raise bolt G and pass beneath the same when pressed into the rear end of lock-case D.

The front jaw, g^3 , of bolt G extends down into the side opening, f' , of key-head F, one vertical edge of said jaw being beveled perpendicular to slot g , as shown at g^4 , Figs. 16 and 17. The jaws of bolt G are held in engagement with notch n and the opening in key-head F by a coiled spring S, located in

bolt-case E and having one end bearing on the outer end of the bolt and the other end on a closing-plate E' , resting on a shoulder e' in said case, being held down by riveting over the outer edge e^2 of said case, as illustrated in Figs. 22 and 23.

It will be observed that plate F^2 of the key-head is of the full diameter of the interior of the lock-case, so as to prevent the introduction of any instrument by which the locking-bolt could be disengaged from the swinging end of the shackle-arm it locks in the case.

Between its front end and the plate F^2 of key-head F a number of plates are located in the lock-case. One or more of these plates H, as may be desirable, are ward-plates and each has on its lower edge a stud h , adapted to engage a longitudinal slot d' in the bottom of the lock-case. Each ward-plate has there-in a central perforation h' , with oppositely-located wings h^2 , as is usual, and in the key K are oppositely-located notches K^2 , adapted to engage the rims of perforations h' as the key is revolved in the lock-case. Between the ward-plates and between said plates and the front of key-head F and the front of the lock-case are closely packed thin spacing-plates M, the openings m in which are so large as to permit the key to turn freely therein. All these plates are held in place by a closing-plate D^2 , having a central keyhole d^2 and a stud d^3 , engaging slot d' , plate D^2 being secured by riveting over the outer edge of the lock-case, as seen in Figs. 11 and 12.

In operating the key is inserted in the lock-case with the prongs K' thereof engaging the perforations f of the end plate of key-head F. The key is then turned until the lip f^2 of the longitudinal opening of said key-head engages beveled edge g^4 of jaw g^3 and raises bolt G until jaw g' is disengaged from notch n of shackle-arm B, when that arm is automatically disengaged from the lock-case by the tension of spring c . The key, after being turned back to restore key-head F to its normal position, is then withdrawn from the lock-case.

In Fig. 14½ is shown a modified form of key-head. The perforations f are omitted in this head, and instead thereof there is a diametrical rib f^3 formed on the outer face of front plate F^2 , adapted to fill the space between and afford a bearing for prongs K' of the key where-by the key-head is revolved.

An unusual number of changes in these locks can be made with one or more ward-plates by changing their relative locations by shifting the positions of any number of spacing-rings to the front or back of said plates. By this means a large number of locks of this pattern can be made in which no two locks can be opened with the same key. The number of these changes can be increased by altering the construction of the keys. The lock herein described is opened by the key K (illustrated in Fig. 18); but instead of locating the notches K^2 opposite each other they may

be placed alternately on opposite sides of the key and extended into the center thereof, as shown in Fig. 19. A further increase can be made in the number of such changes by varying the length of segment F' of key-head F, as illustrated in Fig. 15, where two sizes of such segment are shown, though, as easily understood, that number may be increased.

The adaptability of the lock to such numerous changes for the key makes it particularly valuable, as it proportionably increases the safety of the lock.

I do not limit myself to any particular construction of the locking-bolt and the key-head, or to the form and arrangement of the case containing the same; neither do I restrict myself to the details of construction of the other parts of the lock herein shown and described, as it is obvious that numerous changes may be made therein without departing from the spirit and scope of my invention.

My invention involves a radical departure in the construction and principle of operation of lock mechanism, the invention consisting, broadly, in a shackle divided into sections hinged together at one end, a case carrying a locking-bolt, and a case through which the key passes to actuate said bolt, the said two cases being formed together on the free end of one of said shackle-sections and at an angle the one with the other, and a tongue on the free end of the other shackle-section and constructed to be locked in one of said cases.

Having thus described my invention, what I claim as new, and desire to secure by Letters Patent, is—

1. The combination, in a lock, of a shackle divided into sections hinged together at one end, a case carrying a locking-bolt and a case through which the key passes to actuate said bolt, the said two cases being formed together on the free end of one of said shackle-sections and at an angle the one with the other, and a tongue on the free end of the other shackle-section and constructed to be locked in one of said cases.

2. The combination, in a lock, of a lock-case and a bolt-case formed together at an angle, a shackle constructed to engage the lock-case, and a bolt in the lock-case adapted to engage the shackle when in the lock-case, said bolt being constructed to be disengaged from the shackle by means of a key inserted in said lock-case.

3. The combination, in a lock, of a shackle divided into sections hinged together at one end, a lock-case and a bolt-case formed at an angle with each other on the free end of one of said sections, a bolt in the bolt-case adapted to engage a tongue on the swinging end of the other section, and mechanism in the lock-case adapted to disengage the bolt from said tongue.

4. In a lock, the combination, with a lock-case, of a bolt-case formed on the lock-case at an angle therewith, a bolt having a jaw

constructed to secure a tongue in the lock-case, a jaw on the bolt adapted to be engaged by a key-head, and a key-head constructed to engage said second jaw and disconnect the bolt from said tongue.

5. In a lock, the combination, with a divided shackle, and a bolt-case and a lock-case formed on an arm of said shackle, substantially as described, of a bolt having a jaw constructed to engage a tongue on the other arm of the shackle, a jaw on the bolt adapted to be engaged by a key-head, and a revoluble key-head constructed to engage said second jaw and disconnect the bolt from said tongue.

6. In a lock, the combination, with a lock-case having a passage-way adapted to receive a key-head, of a bolt-case formed on the lock-case at an angle therewith, a bolt having a jaw constructed to secure a tongue in the lock-case, a jaw on the bolt adapted to be engaged by a key-head, a key-head constructed to engage said second jaw and disconnect the bolt from said tongue, and a ward-plate adjustably secured between the key-opening and the key-head in said passage-way, for the purpose specified.

7. In a lock, the combination, with a lock-case having a passage-way adapted to receive a key-head, of a bolt-case formed on the lock-case at an angle therewith, a bolt having a jaw constructed to secure a tongue in the lock-case, a jaw on the bolt adapted to be engaged by a key-head, a key-head constructed to engage said second jaw and disconnect the bolt from said tongue, and an interchangeable ward and a spacing-plate located between the key-opening and the key-head in said passage-way, for the purpose specified.

8. In a lock, the combination, with a lock-case having a passage-way adapted to receive key-heads of different sizes, of a bolt-case formed on the lock-case at an angle therewith, a bolt having a jaw constructed to secure a tongue in the lock-case, a jaw on the bolt adapted to be engaged by a key-head, a key-head constructed to engage said second jaw and disconnect the bolt from said tongue, and means for maintaining the key-head in the path of travel of the bolt, for the purpose specified.

9. In a lock, the combination, with a lock-case having a passage-way adapted to receive key-heads of different sizes, of a bolt-case formed on the lock-case at an angle therewith, a bolt having a jaw constructed to secure a tongue in the lock-case, a jaw on the bolt adapted to be engaged by a key-head, a key-head constructed to engage said second jaw and disconnect the bolt from said tongue, and a ward and a spacing-plate located between the key-opening and the key-head in said passage-way, for the purpose specified.

10. In a lock, the combination, with a divided shackle, and a bolt-case and a lock-case formed on an arm of said shackle, substantially as described, of a bolt having a jaw constructed to engage a tongue on the other arm

of the shackle, a jaw on the bolt, having a beveled edge, and a revolute key-head having a lip thereon adapted to engage said beveled edge and disconnect the bolt from said tongue.

11. The combination, in a lock, of a shackle-arm constructed to be engaged by a bolt, a lock-case, a bolt-case formed at an angle with the lock-case, a bolt, means for preventing the bolt from turning in the bolt-case, a jaw on the bolt adapted to engage the end of said shackle-arm, a jaw on the bolt adapted to be engaged by a key-head, and a key-head in the lock-case, constructed to engage a jaw on the bolt and disconnect the same from the shackle-arm.

12. The combination, in a lock, of a shackle-arm constructed to be engaged by a bolt, a lock-case, a bolt-case formed at an angle with the lock-case, a bolt having jaws separated by a groove, a bar across the bolt-case and engaging said groove, one of said jaws being adapted to engage said shackle-arm and the other of said jaws being adapted to be engaged by a key-head, and a key-head in the lock-case, constructed to engage a jaw on the bolt and disconnect the same from the shackle-arm.

13. The combination, in a lock, of a shackle-arm constructed to be engaged by a bolt, a lock-case, a bolt-case formed at an angle with the lock-case, a bolt having jaws separated by a groove, a bar across the bolt-case and engaging said groove, one of said jaws being adapted to engage said shackle-arm, the other of said jaws having an edge beveled perpendicularly to the groove in the bolt, and a revolute key-head in the lock-case, having a lip constructed to engage said beveled edge, for the purpose specified.

14. The combination, in a lock, of a shackle-arm constructed to be engaged by a bolt, a lock-case, a bolt-case formed at an angle with the lock-case, a bolt, a jaw on the bolt adapted to engage said shackle-arm, a revolute key-head in the lock-case, having an opening therein, and a jaw on the bolt, constructed to engage the opening in the key-head, and having a beveled edge adapted to be engaged by a side of said opening, for the purpose specified.

15. The combination, in a lock, of a shackle-arm constructed to be engaged by a bolt, a lock-case, a bolt-case formed at an angle

with the lock-case, the lock-case having a shoulder therein opposite its intersection with the bolt-case, a revolute key-head in the lock-case, bearing against said shoulder and having an opening therein, a bolt, a jaw on the bolt, constructed to engage the shackle-arm, and a jaw on the bolt, adapted to engage the opening in the key-head, and having a beveled edge adapted to be engaged by a side of said opening, for the purpose specified.

16. The combination, in a lock, of a shackle-arm constructed to be engaged by a bolt, a lock-case, a bolt-case formed at an angle with the lock-case, the lock-case having a shoulder therein opposite its intersection with the bolt-case, a revolute key-head in the lock-case, bearing against said shoulder and having an opening therein, a bolt having jaws separated by a groove, and a bar across the bolt-case, engaging said groove, one of said jaws being adapted to engage said shackle-arm, the other of said jaws being adapted to engage the opening in the key-head, and having a beveled edge adapted to be engaged by a side of said opening, for the purpose specified.

17. In a lock, the combination, with a shackle divided into sections hinged together at one end, the swinging end of one of said sections being adapted to be engaged by a bolt, of a lock-case formed on the swinging end of the other section and tangentially thereto, a radial bolt-case formed with the lock-case, a shoulder in the lock-case, and opposite its intersection with the bolt-case, a bar across the bolt-case, a bolt having a groove engaging said bar, a revolute key-head bearing against said shoulder and having an opening therein, a jaw on the bolt, adapted to engage the end of a shackle, a jaw on the bolt, engaging the opening in the key-head and having a beveled edge adapted to be engaged by a side of said opening, a plate of the diameter of the lock-case and located on the front of the key-head, and an interchangeable ward-plate and spacing-plate interposed between the key-head and the end of the lock-case, substantially as and for the purpose specified.

WILLIAM F. TROAST.
